US00D883828S

(12) **United States Design Patent** (10) **Patent No.:** **US D883,828 S**
(45) **Date of Patent:** **** May 12, 2020**

(54) **CONTAINMENT TRANSMITTER FOR PET RECEIVER**

(71) Applicant: **Radio Systems Corporation**,
Knoxville, TN (US)

(72) Inventors: **Eric A. Ward**, Knoxville, TN (US);
Robert A. Nytko, Knoxville, TN (US);
Kevin A. Zinn, Knoxville, TN (US)

(73) Assignee: **RADIO SYSTEMS CORPORATION**,
Knoxville, TN (US)

(**) Term: **15 Years**

(21) Appl. No.: **29/602,346**

(22) Filed: **May 1, 2017**

(51) LOC (12) Cl. **10-05**

(52) U.S. Cl.
USPC **D10/104.1**

(57) **CLAIM**

The ornamental design for a containment transmitter for pet receiver, as shown and described.

DESCRIPTION

FIG. 1 is a top, front and left side perspective view of a containment transmitter for a pet receiver, showing my new design.

FIG. 2 is a top, front and right side perspective view thereof. FIG. 3 is a bottom, front, and left side perspective view thereof.

FIG. 4 is a bottom, front, and right side perspective view thereof.

FIG. 5 is a front elevational view thereof.

FIG. 6 is a rear elevational view thereof.

FIG. 7 is a right side elevational view thereof.

FIG. 8 is a left side elevational view thereof.

FIG. 9 is a top plan view thereof; and,

FIG. 10 is a bottom plan view thereof.

The broken lines depict portions of the containment transmitter for pet receiver that form no part of the claimed design.

1 Claim, 4 Drawing Sheets
